CLAIM

The ornamental design for a dispense type pill organizer, as shown and described.

DESCRIPTION

FIG. 1 is a perspective view of the dispense type pill organizer showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when it is in use.

The broken lines shown in the drawings are included for the purpose of illustrating portions of the dispense type pill organizer that form no part of the claimed design.
